ROBERT T. BAIN, OF CHICAGO, ILLINOIS.

ELECTRIC SIGNAL FOR VEHICLES.

Application filed May 16, 1925. Serial No. 30,649.

This invention relates to electric signals of the type displayed on the rear of automobiles and other motor vehicles, and belongs more particularly to that class or type 5 of signals intended to display stop and direction indicating signs.

One object of my invention is to provide a signal device of the type described with which shall be combined the usual red tail-light, thereby, through such combination, effecting economy of cost and space. Another object of the invention is to provide, in a signal device of the character mentioned, improved electric mechanism for actuating the movable parts of the signal. 15 Another object is to provide a device whereby, during normal running conditions all of the signalling mechanism shall be covered or occluded and only the regular tail-light shall be displayed. A still further object of the invention is to provide a simple and compact signal mechanism wherein the several movable parts shall all swing around the axis of the tail-light, and wherein the 25 latter may be utilized in the display of the third letter of the stop signal.

Other objects and attendant advantages of the invention will be apparent to persons skilled in the art as the same becomes better 30 understood by reference to the following detailed description, taken in connection with the accompanying drawings wherein I have illustrated one practical and approved embodiment of the invention as designed for use on automobiles, and in which—

Fig. 1 is a front elevation of the signal, showing the oscillating shutter guarding the stop signal in closed position;

40 Fig. 2 is a vertical axial section through the same taken on the line 2—2 of Fig. 3;

Fig. 3 is a vertical section on the offset line 3—3 of Fig. 2 in a plane at right angles to that of Fig. 2;

45 Fig. 4 is a detail in front elevation, on a reduced scale, of the oscillating disc carrying the stop sign and direction indicating arrows;

Fig. 5 is a view in central vertical section 50 of the oscillating signal disc and its supporting and actuating mechanism;

Fig. 6 is a front elevation, on a reduced scale, of the shutter;

55 Fig. 7 is a side elevation, partly in vertical section, of the shutter-actuating device; and

Fig. 8 is a diagram of the lamp and magnet circuits.

Referring to the drawings, 10 designates the circular body member of a sheet-metal casing containing the operating parts of the device and formed with an outwardly flaring front portion 11 having an annular shoulder 12 to seat a sheet-metal disc 13 and, beyond said shoulder a bead 14 adapted to seat the usual retaining ring 15. The other end of the body 10 is closed by a cap 16, to the rear side of which may be attached a post 17 by which the device is fastened to the car.

The front disc 13 is formed with a central horizontal rectangular opening 18, through which the several signals are, at the proper times, made visible. In the center of the opening 18 is located a circular glass lens 19 marginally held at top and bottom by forwardly offset lips 20 and 21 on the upper and lower margins of the opening 18, and by the circular base or attaching flange 22 of an annular hub member 23 behind and concentric with the lens 19; said flange 22 being attached to the rear surface of the disc 13 by screws 24.

Mounted to oscillate on the hub 23 is a sheet-metal disc 25, shown in isolated detail in Fig. 4, having cut out therefrom the letters ST and P on opposite sides of the bearing opening of the disc and also right and left direction indicating arrows 26 and 27 respectively. The median lines of the Stop sign and of the arrows are located sixty degrees apart. It will be observed from Fig. 4 that the central bearing opening of the disc 25 is formed with an upper half bearing 28 that fits the bearing hub 23, and with a lower half bearing 29 formed on a slightly greater radius, thereby forming between the half bearing 29 and the lower half of the hub 23 a narrow semi-circular slot for a purpose hereinafter disclosed. Attached to the rear side of the disc 25 and concentrically with the bearing opening thereof is a ring 32, on the lower side of which is a rearwardly extending connector arm 33 supporting at its opposite end a smaller ring 34. The ring 33 has a bearing on the hub 23, and the ring 34 has a similar bearing on the inner end portion of a threaded lamp socket sleeve 35 that passes through central openings in the rear cap 16 and in a disc 36 lying a slight dis-

tance inwardly of and parallel with the cap 16 and secured to the circular body 10 of the casing by inwardly bent lugs 37 on the latter and attaching screws 38. Between the discs 16 and 36 is a spacing washer 39 encircling and locked on the sleeve 35; and on the outer end of the sleeve 35 is a washer 40 bearing against the outer side of the post 17, and a confining nut 41 centrally apertured to admit the circuit wires 42 of the tail lamp 43; the shank of the latter being mounted in an insulation plug 44 mounted in the sleeve 35. The lamp 43 lies behind and is coaxial with the lens 19; and on the rear surface of the lens 19 is secured a circular red disc 45 of a diameter slightly less than the diameter of the lens 19, so that the rays from the lamp show red through the solid central portion of the lens, and show white through the narrow annular portion thereof around the red portion, thus forming the letter O constituting the third letter of the stop sign.

Mounted on the bearing hub 23 between the fixed discs 13 and the oscillatory disc 25 is the hub of a shutter 46, having substantially the outline form and dimensions of the opening 18. When this shutter is in horizontal position, the two wings thereof are adapted to occlude the letters ST and P of the Stop sign, and, when oscillated to a vertical position leave the said letters exposed through the rectangular opening 18. On the hub of the shutter 46 is an inwardly directed lug 47 that extends through the slot formed between the periphery of the bearing hub 23 and the lower half bearing 29 of the disc 25, the inner end of said lug 47 fitting into a notch 48 (Fig. 3) formed in the inner periphery of a ring 49 mounted on the hub 23 directly behind the ring 32. Mounted on the sleeve 35 just in front of the ring 34 is an inner ring 50, and these two rings are connected at their outer peripheries by a connector arm 51 formed with a radially extending lug 52, as clearly shown in the detail view Fig. 7.

Reverting to the actuating device of the disc 25, shown in detail in Fig. 5, the inner bearing ring 34 is provided with a depending leg 53 terminating in a rectangularly bent toe 54.

The signal disc 25 and the shutter 46 are actuated by electro-magnets mounted wholly within the casing; and describing this actuating mechanism, and referring to Figs. 2 and 3, attached to the inner face of the disc 36 as by screws 55 is a magnet supporting frame consisting of an approximately semi-circular flat bar 56 formed with a central forwardly offset U-shaped portion 57 and with forwardly extending end portions 58. Mounted between and supported by the sides of the central offset U-portion of the frame is an arc-shaped electro-

magnet 59; and similarly mounted between the side members 57 of the centrally offset U-shaped portion and the end members 58 of the frame are arc-shaped magnets 60 and 61, respectively. These magnets are of the solenoid type, as clearly shown in Fig. 3, and it will be observed by reference to Fig. 2 that the intermediate magnet 59 is forwardly offset within the casing relatively to the end magnets 60 and 61. The lower heads of the spools of the magnets 60 and 61 consist of iron discs 60' and 61', for a purpose hereinafter disclosed.

Attached at its center by a screw 62 to the leg 53, and supported on the toe 54 of the latter is a long approximately semi-circular armature bar, the two halves 63 and 64 of which constitute the armatures of the magnets 60 and 61. When the magnet 60 is energized, its armature 63 swings the signal disc 25 sixty degrees in a clockwise direction, viewing the front of the indicator, bringing the right hand direction indicating arrow 26 into view through the opening 18. When the armature 61 is energized its armature 64 swings the signal disc 25 sixty degrees in a counter-clockwise direction, bringing the left hand direction indicating arrow 27 into view through the opening 18. When both magnets 60 and 61 are idle, gravity causes the armature to occupy the intermediate or neutral position shown in Fig. 3, in which position the stop sign occupies the opening 18.

To prevent chattering of the disc 25 when in its normal position with the Stop sign occupying the opening 18, I provide a simple automatic lock shown in Figs. 2 and 3. To the lower end of the leg 53 is attached by the screw 62 a rearwardly extending foot 65, the free end of which normally lies between the proximate ends of a pair of like levers 66 that are pivoted at 67 on the disc 36. The upper ends of these levers lie closely adjacent to the lower heads 60' and 61' of the spools of the magnets 60 and 61. When either of these magnets is energized, the magnetic lines of force acting through the iron heads 60' or 61' attract the upper end of the lever, thereby swinging the lower end of the lever clear of the foot 65, and thus permitting the armature to be drawn into the magnet. Upon de-energization of the magnet, the lever drops back by gravity to its normal position, and as the foot 65 returns to central position it depresses and drops behind the lower end of the lever and is relocked by the latter.

68 designates the curved armature bar of the central shutter actuating magnet 59. This armature at its lower end is connected to the lug 52 which oscillates the ring 49 to which the shutter 46 is connected by its lug 47. Gravity normally maintains the armature 68 in the withdrawn position 130

shown in Fig. 3, which corresponds to the horizontal position of the shutter 46 closing the opening 18. When the magnet 59 is energized, the armature 68 is drawn upwardly into the magnet, and the shutter 46 is swung to vertical or approximately vertical position, exposing the underlying signal (either Stop or one of the direction indicating arrows) through the opening. When the magnet 59 is de-energized, the gravity of the armature 68 and the radial attaching lug 52 thereof causes them to return to the positions shown in Fig. 3, which corresponds to the horizontal or closing position of the shutter.

The description of the operation will best be understood by reference to Fig. 8 which is a diagram of the lamp and magnet circuits, and the switches employed therein to effect the desired manipulation of the indicator. Referring to this view, 70 designates a battery or other source of current, from the opposite poles of which circuit lines 71 and 72 extend to and through the lamp 43. In the line 71 may be a cut-out switch 73, not ordinarily used, and in the line 72 is a two-way switch 74 that is closed, as shown by its full line position, when the light 43 is regularly burning as when driving at night. Connected to one limb (71) of the lamp circuit is a line 75, which includes the winding of the magnet 61 and terminates in a contact 76. Connected to the line 75 is a line 77 that includes the winding of the magnet 59 and terminates in branches 78, 79 carrying contacts 80 and 81 respectively. Connected to the line 77 is a line 82 that includes the winding of the magnet 60 and terminates in a contact 83. Pivoted at 84 is a two-arm switch, one arm 85 of which may be swung by the hand or foot of the operator to close a circuit through the contact 76, 80, and the other arm 86 of which may be similarly swung to close a circuit across the contacts 81, 83. Connected to the line wire 72 of the lamp circuit is a line 87 that includes a normally open switch 88 closed when required in any approved manner. The other end of line 87 is connected at 89 to the line 77; and from the same point 89 there is led a line 90 that terminates in a contact 91 adapted, when the lamp circuit is open as during daylight driving, to be engaged by the switch 74, as shown by the dotted line position of the latter. A line 92 connects the center of the two-arm switch 85, 86 with the line 87.

Describing now the mode of manipulating and controlling the indicator, and bearing in mind that the shutter 46 is normally kept closed by the gravity of its actuating armature 68 and that the Stop sign normally occupies the opening 18 behind the closed shutter due to the gravity of its actuating armatures 63, 64, during daylight

driving the switch 74 is thrown to the dotted line position shown in Fig. 8, wherein the lamp circuit is broken. When the car is stopped by the application of the foot brake, the switch 88 is closed. This closes a circuit through the shutter actuating magnet 59 causing the shutter to open; the circuit, starting from the switch 88, consisting of line 87, battery 70, line 71, line 75 to line 77, line 77 including magnet 59, and line 87 to the closed switch 88. At the same time the lamp is lighted by a branch or shunt circuit consisting of line 71 beyond line 75, lamp 43, line 72, switch 74 and line 90 which is connected to line 77 at 89.

When driving at night, the two-way switch 74 is closed as shown by its full line position, and the light is continuously burning, and the shutter is swung to display the stop signal upon closure of the pedal-actuated switch 88 through the circuit already described.

If the right-hand turn signal is to be displayed by the arrow 26, the switch arm 86 is swung to connect the contacts 81 and 83. This closes the circuit through magnet 60 which, starting at contact 83 may be traced as follows; line 82 through magnet 60 to line 77, line 77 to line 75, line 75 to line 71, through the latter and the battery 70 to line 87, lines 87 and 92 to switch arm 86 and through the latter to contact 83. At the same time that the signal disc 25 is thus actuated to display the arrow 26, a shutter-actuating branch circuit is closed through the magnet 59, the same consisting of line 77 in which the magnet 59 is included, branch line 79, and switch arm 86.

Similarly, if the left-hand turn signal is to be displayed by the arrow 27, the switch arm 85 is swung to connect the contacts 76 and 80; and the magnet 61 is then energized through a circuit which, starting at contact 76, comprises line 75 through magnet 61, line 71, battery 70, lines 87 and 92, and switch arm 85. At the same time the shutter is thrown to open position by energizing the magnet 59 through a branch circuit consisting of line 77, including magnet 59 and branch 78.

From the foregoing it will be seen that the throwing of the two-arm switch 85, 86, to display either of the direction indicating arrows 26 and 27, energizes not only the signal disc actuating magnet 60 or 61, but simultaneously energizes the shutter actuating magnet 69, and also energizes the lamp circuit, so that the shutter is opened at the same time that the intended signal is displayed through the opening normally closed by the shutter.

When driving in daylight, with the switch 74 in the dotted line position and the lamp circuit normally broken, if the direction in-

dicating switch 85, 86 is thrown to either side to open the shutter and swing either arrow into indicating position, the lamp will be temporarily lit and the arrow illuminated, the lamp circuit being then completed from switch 74 through lines 90, 77 and branches 78, 79 instead of through lines 72, 87 and 92, as when driving at night.

While I have herein shown and described one practical and compact form in which the invention may be embodied, it is manifest that many of the specific details of structure and arrangement may be considerably varied without departing from the operative principle of the invention or sacrificing any of its benefits and advantages. Hence, I do not limit the invention to the particular form herein shown and described for purposes of illustration, but reserve all such variations, modifications and mechanical equivalents as fall within the spirit and purview of the appended claims.

I claim—

1. In an electric vehicle signal of the character described, the combination of a casing having a front wall formed with a transverse opening therein, an electric lamp behind said opening, an annular bearing member on said wall disposed coaxially with said lamp, a colored translucent disc of less diameter than the internal diameter of said bearing member mounted in said opening coaxially with said bearing member and lamp, a plate mounted to turn on said bearing member and having the letters ST and P cut therein on opposite sides respectively of said bearing member, and means for oscillating said plate to move said letters into and out of the field of said opening.

2. In an electric vehicle signal of the character described, the combination of a casing having a front wall formed with a transverse opening therein, an electric lamp behind said opening, an annular bearing member on said wall disposed coaxially with said lamp, a colored translucent disc of less diameter than the internal diameter of said bearing member mounted in said opening coaxially with said bearing member and lamp, a plate mounted to turn on said bearing member, said plate having the letters ST and P cut therein in a straight line on opposite sides respectively of said bearing member and also a direction-indicating arrow disposed at an angle to the line of direction of said letters, and means for oscillating said plate to move either said letters or said arrow into and out of the field of said opening.

3. In an electric vehicle signal of the character described, the combination of a casing having a front wall formed with a transverse opening therein, an electric lamp behind said opening, an annular bearing member on said wall disposed coaxially with

said lamp, a colored translucent disc of less diameter than the internal diameter of said bearing member mounted in said opening coaxially with said bearing member and lamp, a plate mounted to turn on said bearing member, said plate having the letters ST and P cut therein in a straight line on opposite sides respectively of said bearing member and also a pair of direction-indicating arrows disposed at angles of substantially sixty degrees to each other and to the line of direction of said letters, and means for turning said plate to bring either said letters or either one of said arrows into and out of the field of said opening.

4. In a vehicle signal, the combination of a casing having a front wall formed with a transverse opening therein, an electric tail-light lamp behind said opening, a lens mounted in said opening in front of said lamp and formed with a central colored portion and an uncolored annular portion around said central portion, a plate behind said opening having the letters ST and P cut therein on opposite sides respectively of said lens, the annular uncolored portion of the latter forming the O of the Stop sign, and a shutter movable to cover and uncover said opening.

5. A specific embodiment of the subject-matter of claim 4, wherein the shutter has substantially the outline form and dimensions of the transverse opening and is pivoted on an axis coincident with the axis of the lens.

6. In combination with the subject-matter of claim 4, an electro-magnet mounted in the casing, and actuating connections therefrom to the shutter.

7. In a vehicle signal, the combination of a casing having a front wall formed with a transverse opening therein, an electric tail-light lamp behind the said opening, a lens mounted in said opening in front of said lamp and formed with a central colored portion and an uncolored annular portion around said central portion, a plate behind said opening having the letters S, T and P cut therein on opposite sides respectively of said lens, the annular uncolored portion of the latter forming the letter O of the Stop sign, a shutter of substantially the outline, form and dimensions of the transverse opening pivoted on an axis coincident with the axis of the lens and movable to cover and uncover said opening, and a solenoid magnet mounted in the casing having its armature connected to said shutter for swinging the latter.

8. In a vehicle signal, the combination of a circular casing having a front wall formed with an oblong transverse opening therein, an electric tail-light lamp centrally in rear of said opening, a circular lens mounted in said opening in front of and coaxial with

said lamp and formed with a central colored portion and an uncolored annular portion around said central portion, a disc rotatably mounted in rear of said front wall coaxially with said lamp and lens, said disc having the letters ST and P cut therein in a straight line on opposite sides of its axis and a direction-indicating arrow disposed at an angle to the line of direction of said letters. a shutter for opening and closing said opening rotatably mounted on one side of said front wall, an electro-magnet mounted in said casing and operatively connected to said disc, and another electro-magnet mounted in said casing and operatively connected to said shutter.

9. In a vehicle signal, the combination of a circular casing having a front wall formed with an oblong transverse opening therein, an electric tail-light lamp centrally in rear of said opening, a circular lens mounted in said opening in front of and coaxial with said lamp and formed with a central colored portion and an uncolored annular portion around said central portion, a disc rotatably mounted in rear of said front wall coaxially with said lamp and lens, said disc having the letters ST and P cut therein in a straight line on opposite sides of its axis and a pair of direction-indicating arrows cut therein disposed at angles of substantially sixty degrees to each other and the line of direction of said letters, a shutter for opening

and closing said opening rotatably mounted between said front wall and said disc, a pair of solenoid magnets mounted in said casing with their armatures connected to said disc and operating, when idle, to maintain said letters ST and P in the field of said opening and, when energized, to respectively bring said direction-indicating arrows into the field of said opening, and another solenoid magnet mounted in said casing and operative to swing said shutter into and out of occluding position relatively to said opening.

10. In a vehicle signal, a sign Stop in which the letter O is the tail light of the vehicle, in combination with means to illuminate and extinguish the illumination of the letters S, T and P.

11. In a vehicle signal, a tail lamp forming the letter O, a plurality of signals, one of which comprises the letters S, T and P, and means to individually bring said signals into cooperative relation with said letter O.

12. In a combined vehicle tail light and speed indicating signal, a tail light including a portion constituting a representation of the letter O, and means co-operating with the tail light for making certain letters visible on opposite sides of the tail light letter for forming a speed signal.

In witness whereof I have hereunto set
ter for forming a speed signal.

ROBERT T. BAIN. [L. S.]
